UNITED STATES PATENT OFFICE.

NATHAN HEARD, OF NEWTON, MASSACHUSETTS, ASSIGNOR TO DRAPER CORPORATION, OF HOPEDALE, MASSACHUSETTS, A CORPORATION OF MAINE.

LOOM DOBBY.

Application filed January 30, 1928. Serial No. 250,355.

This invention relates to a dobby mechanism for looms in which a plurality of indicating fingers are employed for controlling the operation of the harnesses. These indicating fingers which are of metal are frequently broken or injured and have to be removed or replaced. It is highly desirable that when such removal and replacement takes place, the position of the remaining fingers shall not be substantially disturbed. It is further necessary that the indicating fingers when in operation shall be prevented from rising from the axis on which they rock when they are lifted by the risers of the pattern chain.

It is the object of the present invention to provide a simple and efficient construction for mounting the indicating fingers to secure the proper rocking movement and a construction which will permit the expeditious removal and replacement of any finger without disturbing the remainder.

It is the object of the present invention to secure the foregoing result by a construction forming a part of the dobby and which does not require removal therefrom when an indicating finger is to be removed or replaced.

These and other objects and features of the invention will appear more fully from the accompanying description and drawings.

As the invention is concerned only with one feature of the dobby construction and as the general construction and operation of the dobby mechanism is well known and familiar to those skilled in the art, and as the invention is applicable to a wide range of dobby constructions, it is only necessary here to illustrate and describe a portion of an ordinary type of dobby mechanism, together with a preferred form of the invention embodied therein.

In the drawings:

Fig. 1 is a view chiefly in transverse vertical cross section taken through the fulcrum axis of the indicating fingers.

Fig. 2 is a view in side elevation and partially in longitudinal vertical cross section of the mechanism.

Fig. 3 is a detail showing the position of the fulcrum shaft and finger when a finger is to be removed.

The dobby comprises the usual frame having the vertical sides 1 connected by suitable transverse members including the front bar

2. The indicating fingers are arranged in a transverse series and are all of the same shape except at the rear ends. One set of fingers 3 have straight rear ends 4 cooperating with lifting rods 5 which control the upper hooks 6 of the dobby, not shown. The other set of indicating fingers 6 have their rear ends 7 upturned and directly controlling the lower hooks 8 of the dobby. The indicating fingers normally rest at their front ends on the bar 2. These indicating fingers are controlled by risers 9 on the usual pattern chain running over a sprocket wheel 10 mounted on a shaft 11 extending transversely beneath the fingers. When a riser 9 is moved by the pattern chain beneath a finger, the finger is rocked, depressing the rear end and thus allowing the corresponding hook to engage with the usual reciprocating knife 12 and shift the proper harness, all in a manner well known and familiar to those skilled in the art.

In this construction the entire series of fingers are fulcrumed upon a fulcrum shaft 13 journaled at its ends in the frame sides 1. Between the frame sides this shaft is of segmental cross section, thus presenting the flat surface 14 and the arcuate surface 15. Each indicating finger is provided with a circular bearing aperture 16 of a diameter corresponding to the shaft so that it fits closely the shaft 13 and this circular bearing aperture has an opening through the bottom edge of the finger. One wall 17 of this opening is tangent with the aperture 16 and the other wall 18 is spaced from the wall 17 a distance corresponding to the shorter diameter of the segmental cross section of the fulcrum shaft.

In the construction shown, the flat surface 14 of the fulcrum shaft is substantially horizontal and the opening from the circular bearing aperture 16 through the bottom of the finger is substantially vertical when the parts are in the normal working position shown in Figs. 1 and 3. The indicating fingers then rock on the fulcrum shaft 13 and are prevented from rising off from the shaft by reason of the fact that the opening from the bearing aperture 16 in each finger is narrower than the greater diameter of the fulcrum shaft. When it is desired to remove and replace a finger, the fulcrum shaft is rotated on its axis substantially 90°, bringing the flat surface 14 parallel with the walls of the opening from the bearing aperture 16 through the bottom edge of the finger or into the position

shown in Fig. 2. When in this position, the finger may readily be lifted off from the fulcrum shaft and one finger 6 is shown in Fig. 2 as removed from the shaft. When a finger is thus being lifted off, it will be seen that the remaining fingers retain their place on the fulcrum shaft and are not disturbed. While the flat surface 14 of the fulcrum shaft is thus shown as occupying either a substantially horizontal or a substantially vertical position, it is obvious that any suitable angular relation may be adopted which will enable the fingers to have the proper rocking movement and to be removed and replaced. The set of fingers 6 having the upturned rear ends 7 may have to be swung through quite a wide angle to enable them to be removed from the dobby frame, as shown in dotted lines in Fig. 2. The comb is herein shown as in two parts, 19 and 20, and located in a position where it will not interfere with the ready removal and replacement of the fingers.

The two positions of the fulcrum shaft, that is, the position shown in Fig. 3 when the indicating fingers are working and the position shown in Fig. 2 when a finger is to be removed and replaced, may be determined by any suitable means. In the construction illustrated, the fulcrum shaft 13 is shown as having a head 21 at one end bearing against the side frame, while at the other end the shaft is provided with a radially projecting arm 22 and the frame is provided with stops 23 cooperating with the arm 22 and positioning the shaft in either of the respective desired positions.

It will thus be seen that a construction is provided in which there is no additional member other than the fulcrum shaft for supporting the fingers either in operative position or when they are to be removed and replaced and that this fulcrum shaft always forms a permanent part of the dobby and is not removed therefrom when the fingers are to be removed and replaced. It will also be seen that the construction is such as to maintain the indicating fingers in proper working position while by a simple rotary movement of the shaft each finger is freed for removal and replacement without disturbing the remainder.

Having thus described the invention, what is claimed as new, and desired to be secured by Letters Patent, is:

55. 1. In a loom dobby the combination of a frame, a fulcrum shaft journalled in the frame sides and having therebetween a portion of segmental cross section, and a series of indicating fingers fulcrumed on the shaft and each having a circular bearing aperture of a diameter to fit the shaft with an opening through the bottom edge, one wall of said

opening being tangent with the aperture and the other wall being spaced therefrom a distance corresponding to the shorter diameter of said segmental portion whereby, when the flat surface of the shaft is at the bottom, the fingers rock on the arcuate surface and are locked against removal and, when the shaft is rotated substantially ninety degrees, any finger may be lifted off the shaft and replaced without disturbing the remainder. 65

2. In a loom dobby having the construction defined in claim 1, the combination therewith of an arm projecting radially from one end of the fulcrum shaft and stops on the frame which when engaged by the arm position the shaft in the said rotary positions. 75

3. In a loom dobby having the construction defined in claim 1, the combination therewith of means for positioning the fulcrum shaft in either of said rotary positions. 80

4. In a loom dobby the combination of a frame, a fulcrum shaft journalled in the frame sides and having therebetween a portion of segmental cross section, and a series of indicating fingers fulcrumed on the shaft and each having a circular bearing aperture of a diameter to fit the shaft with an opening through the bottom edge, one wall of said opening being tangent with the aperture and the other wall being spaced therefrom a distance corresponding to the shorter diameter of said segmental portion, and means for rotarily positioning the fulcrum shaft either with the flat surface at the bottom and perpendicular to the tangent walls of said finger openings or parallel therewith whereby, when in the former position, the fingers rock on the arcuate surface and are locked against removal and, when in the latter position, any finger may be lifted off the shaft and replaced without disturbing the remainder. 95

5. In a loom dobby the combination of a frame, a fulcrum shaft journalled in the frame sides, a series of indicating fingers fulcrumed on the shaft, the bearing portion of the shaft being of segmental cross section and the fingers each having a similar bearing aperture opening at the bottom edge cooperating with the bearing portion of the shaft to permit the fingers to rock without removability when the shaft is in one rotary position and to permit any finger to be lifted off and replaced without disturbing the remainder 100 when the shaft is in another rotary position. 105

6. In a loom dobby having the construction defined in claim 5, the provision of means for positioning the shaft in either of said rotary positions. 110

In testimony whereof, I have signed my name to this specification. 115

NATHAN HEARD.
